UNITED STATES PATENT OFFICE

2,444,223

TUYÈRE

Martin De Lin, Fort Wayne, Ind.

Application June 30, 1945, Serial No. 602,532

2-Claims. (Cl. 110—44)

1

This invention relates to improvements in tuyères through which air is supplied to fuel as it is fed into a furnace.

Generally, air supplied through tuyères into the combustion chambers of furnaces is directed radially toward or from the axes of the tuyères which causes movement of the burning gases to roll radially in the combustion chambers which more or less stifles the process of combustion. In the instant invention an object is to supply a proper amount of air under pressure distributed uniformly about the perimeter of the fuel body in such manner as to cause the flame of the burning fuel to swirl uniformly in the combustion chamber continuously in a definite direction, thus to obviate formation of eddies or other impedimenta to combustion of the fuel gases.

Another object of the invention is to construct a tuyère made up of a series of units telescopically arranged to form a continuous complete circuit, and shaped so as to provide a corresponding series of outlet air passageways directed generally around a circuit so that air, introduced into the combustion chamber of the furnace, swirls uniformly therein about a common axial center, thus to avoid conflicting movements of fuel gases during combustion thereof.

And a still further object of the invention is to provide a tuyère through which fuel and air are supplied to the combustion chamber of a furnace so as to insure uniformity in the movement and density of the fuel gases during passage thereof through the combustion chamber.

Other objects and advantages of the invention appear in the following description.

An illustrative embodiment of the invention is shown in the accompanying drawings, in which—

Fig. 1 is a fragmentary top plan view of a structure in which the invention is incorporated showing a series of tuyère units telescopically arranged in operative position;

Fig. 2 is a rear end elevational view of one of the tuyère units;

Fig. 3 is a front end elevational view of a similar tuyère unit;

Fig. 4 is a fragmentary elevational view showing two of the telescopically arranged units, the section being along a vertical concentric plane located substantially midway between the inner and outer walls of the series of tuyère units, as indicated by the dotted line $x-x$ of Fig. 1;

Fig. 5 is an elevational view showing a section of the tuyère structure on the line $y-y$ of Fig. 1; and

Fig. 6 is a schematic diagrammatical top plan 55 cross-piece. The bottoms of the tuyère units are

2

view of the tuyère structure arranged in connection with the fuel and air supply means, drawn to a reduced scale.

The illustrative embodiment of the invention consists of a tuyère structure in which a series of similar tuyère units 7 are telescopically arranged in relation with each other upon a supporting base 8 and form an annulus.

Each tuyère unit consists of an arch-shaped hollow casting the front end of which is enlarged to form a bonnet 9, and the rear end of the casting is of lesser dimensions so as to be received telescopically within the bonnet of the next adjacent tuyère unit. The exterior lateral walls of the rear end portion of each unit have outwardly extending flanks 10 and 11 that snugly fit against the corresponding interior walls of the bonnet of an adjacent unit. The flanks have lateral outwardly extending projections 10' and 11' respectively, on their lower portions at points spaced from the rear end of the unit that serve as stops by which is limited the projection of the rear end of one unit into the bonnet of an adjacent unit by having contact with the outer face thereof, so that when the units are telescopically assembled there is left between the bonnet of each unit and the rear end of the adjacent unit an open space 12 between the opposing walls of the telescoped portions of the units, constituting an air passageway for the outlet of air.

These passageways extend continuously from the flanks 10, over the crests of the telescoped portions of the units and down to the flanks 11 where they terminate. In this manner there is established an annular series of air outlet passageways uniformly spaced around the crest of the annulus formed of the units. As the tops of the flanks 10 on the inner walls of the units terminate at a lower level than that of the tops of the flanks 11 on the outer walls thereof, the preponderance of air emitted through the passageways is in the region bordering the inner wall of the annulus, while a minor portion is along the crest and adjacent upper portion of the outer wall thereof.

The tuyère units are assembled in position upon the base 8 which consists of an annular air duct 13 the upper wall 14 of which has made therein an annular series of openings 15, and has a corresponding series of radial arms 16 that intervene therebetween. Each unit 7 has an interior cross-piece 17 that overlies the corresponding arm 16 of the base, when the unit is in place, where it is held by a bolt 18 that connects the arm and

open to receive air from the duct through the openings 15.

The air duct 13 is connected with a suitable source of air under pressure (not shown), by means of a conduit 19 as in the usual practice, and a fire pot 20 is arranged concentrically with and encompassed by the air duct as in the usual manner. The fire pot is supplied with fuel from a suitable source (not shown) through a feed pipe 21 having therein a common conveyer screw 22. 10

Operation

In using the invention, fuel is supplied through the feed pipe 21 to the fire pot continuously or periodically with more or less regularity, and air is likewise supplied to the air duct 13 through the conduit 19 by means of any suitable stoking apparatus (not shown) for such purpose. While the fuel is fed into the fire pot, air from the air duct is emitted through the outlet passageways 12 in a common direction around the crest of the annulus so the body of fuel in the fire pot is completely encompassed by a swirling stream of air by which is stimulated combustion of the fuel body with uniformity. This action is advantageous and of value as the flame, due to combustion, is circulated evenly and entirely around the circumferential region of the fuel body with consequent uniformity and thoroughness of combustion thereof.

Variations from the particular construction above disclosed may be resorted to by the exercise of skill in the art, without departure from the spirit or scope of the invention.

What I claim is:

1. A tuyère structure consisting of a hollow annulus formed of a series of telescopically arranged units, one end of each unit having a bonnet and its opposite end portion being adapted to enter the bonnet of an adjacent unit, the outer and inner exterior walls thereof having a lat-

erally projecting flank extending upward part way toward the crest of the unit adapted to fit against the corresponding inner wall of the bonnet so there is left a space between the crest of said end portion and the opposing inner face of said bonnet to form an air passageway that extends from one flank, over the crest of said end portion, to the corresponding opposite flank, and a stop on each flank adapted to limit projection of said end portion into the corresponding bonnet by having contact therewith.

15 2. A tuyère structure consisting of a hollow annulus formed of a series of telescopically arranged units, one end of each unit having a bonnet and its opposite end portion being adapted to enter the bonnet of an adjacent unit, the outer and inner exterior walls thereof having a laterally projecting flank extending upward part way toward the crest of the unit adapted to fit against the corresponding inner wall of the bonnet so there is left a space between the crest of said end portion and the opposing inner face of said bonnet to form an air passageway that extends from one flank, over the crest of said end portion, to the corresponding flank.
